Thos. Stratton

UNITED STATES PATENT OFFICE.

ALBERT M. AYERS, OF NUTLEY, NEW JERSEY.

DUPLICATING MACHINE.

Application filed May 19, 1921. Serial No. 470,806.

To all whom it may concern:

- Be it known that I, ALBERT M. AYERS, a citizen of the United States, residing at Nutley, in the county of Essex and State of New Jersey, have invented certain new and useful Improvements in Duplicating Machines, of which the following is a specification, reference being had therein to the accompanying drawing.
10. My invention relates to improvements in duplicator machines and more particularly has reference to that type of machine in which the surface upon which the impression is taken and from which duplicate records are made is rotated in such a manner as to take up and print successive sheets of paper from a stack, automatically depositing the same in a substantially flat and uniform stack, the entire operation being practically 20 automatic, except for two simple hand movements.

In the accompanying drawings, I have illustrated in Fig. 1 in side elevation partly broken away and partly in dotted outline a suitable form of duplicator machine embodying an application of my invention. Fig. 2 is a plan view looking down upon the same. Fig. 3 is a section on the line 3—3 of Fig. 2. Fig. 4 is a similar view to Fig. 3, except that it shows the retaining roll in the position in which it rises to lift the sheet against the printing roll, and Fig. 5 is a front elevation partly broken away illustrating the sheet gripping mechanism.

35. Referring now more particularly to Figs. 1 to 4 inclusive, 6 indicates the legs of the machine upon which the frame 7 is mounted as shown, and 8—9—10 indicate the transverse braces connecting the side frames 7. 40. 11 indicates a suitable rack attached to the cross bar 12 at the opposite end of which corresponding with the position of the rack 11 is secured a guide bar 13. The rack 11 it will be observed meshes with the pinion 14 45 pivoted in the frame 15, and the pinion 14 in turn meshes with the pinion 16, also rotatably secured upon said frame and which in turn engages the large pinion 17 mounted upon the axis 18 of the large roll. This 50 large roll is provided with a semi-circular portion 19 over which the gelatinous strip 20 passes feeding from the roll 21 to the roll 22 as shown, thus presenting a printing surface from the idlers 23 to 24 covering not less than half the entire circumference of the 55 said roll 19. From the foregoing it will be

obvious that the printing surface of the large roll extends from 23 to 24 and that the surface may be renewed or changed by turning the rolls 22 and 23 as follows: Upon the axis of the roll 22, a square end 22' is provided to receive a key and is also provided with a ratchet 25 engaged by the pawl 26 so that by rotating the key leftwardly or anti-clockwise, the roll 22 will draw off from the roll 21 a sufficient amount of the gelatinous surface to prepare a new printing surface thereupon, the roll 21 being also provided with a ratchet such as 27 and pawl 28 as shown, to prevent slippage and for maintaining the gelatin sheet or web under suitable tension so as to present a smooth and uniform printing surface.

29 indicates the tray upon which the stack of sheets, such as letterheads, are placed 75 preferably beneath the holder 30 pivoted at 31 as shown, and the tray 29 it will be observed is elevated at an angle by the brace 32 upon which it is pivoted at 33 as shown. Beneath the free or righthand end of the tray 30 is a bar 34 pivotally mounted and having projecting arms such as 35 which pass beneath the tray as shown and which are normally projected upwardly against the tray by the spring 36. Another arm 37 also 85 pivotally mounted upon the bar 34 projects leftwardly in the path of the pin 38 upon the bracket 39 which in turn is secured upon the hand bar 40 the righthand end of which is turned up as indicated at 41 so that it can 90 be conveniently gripped and pulled laterally when desired. This bar 40 it will be observed is also pivotally mounted at 33 and passes through the guide 42.

In the operation of the machine, the finger 95 piece 41 being gripped is pulled rightwardly looking at Fig. 1, thus drawing the tray 29 beneath the roll 19, and of course the sheets of paper upon the tray. By now lifting the bar 40 the top sheet is brought 100 in contact with the gelatinous surface 20 and adheres thereto, after which the finger piece 41 being pushed leftwardly causes the projection 43, extending from beneath the tray 29, to ride upon the inclined and preferably resilient surface 44, thus bringing the roller 45 against the sheet now adhering to the gelatinous sheet as aforesaid. The next operation is to draw the sheet rightwardly looking at Fig. 1, which automatically rotates the large cylinder, leaving the 105 inked impression upon the sheet, and for 110

2
this purpose the hand is now released from the lever 40—41 and the cam handle 46 is seized pushing the grip leftwardly in the direction of the free end of the sheet of paper extending rightwardly. A detail of this gripping device is shown to better advantage in Fig. 5 and comprises a base guide 48 within which the vertical standard 47 may slide rightwardly and leftwardly looking at Fig. 1. From the cross bar 12 a bracket 49 projects and provides bearing for the bar 50 which in turn is secured at the inner end to the block 51 projecting from said standard 47 and upon said bar 50 is an extension coiled spring 52 which when the standard 47 is pushed leftwardly is compressed. By now rotating clockwise the handle 46 secured to the bar 53, said bar having a cam 54, the latter is rotated lifting the lower jaw 55 which coming in contact with the upper jaw 56 though normally separated by the spring 57, grips the free end of the paper projecting beneath the lower roll 19 and by now gripping the hand rail 58 and pulling rightwardly looking at Fig. 1 the sheet is drawn beneath the roller which by contact with the web 20 transfers the impression from the roller to the sheet and the gripper remains in its leftward extended position against the compression of the spring 52 until the sheet finally releases from the gelatin web 20, thereby causing the gripping device to fly rightwardly, the handle 46 striking the inclined side 58' of the hand bar 58 which thereby automatically throws the lever 46 upwardly or anti-clockwise thereby releasing the jaws and allowing the sheet of paper to fall between the side frames 7 where the sheets stack in a substantially flat and uniform manner and from which position they can be conveniently removed.

Upon the tray 29 are side members 60 which may be moved in the direction of each other or may be separated merely to serve as a sort of guide for the paper stacked upon the tray and the same applies to the plate 61

formed at the hinge of the pivoted arm 30. 62 indicate stops in the path of the rack 11 and guide bar 13.

From the foregoing it will be apparent that the relative position of the large cylinder and its driving mechanism may be varied by disengaging the rack 11 and pinion 14. It will be readily observed that by lifting the handle 58 when at its extreme rightward position, looking at Fig. 1, the entire frame including rack 11, guide bar 13, and cross brace 12, may be raised from driving engagement and the large gear 17 may then be rotated to the desired position before the frame is replaced in its driving position, thus permitting such adjustment of the parts as may be found desirable.

Of course it will be understood that various modifications may be made in the construction and arrangement of parts without departing from the spirit of the invention as claimed.

I claim:

In a machine of the class described, means for engaging the ends of sheets successively upon a printing roller, means for gripping and drawing the sheet beneath the roller and while in contact therewith, and means for releasing the sheet substantially simultaneously with its release from said roller, said means for engaging said sheets and said roller comprising a movable tray upon which said sheets are stacked, and means for lifting said tray in the direction of said roller and in combination therewith a sheet holding roller adapted to press said sheet against said first mentioned roller during the entire period of the printing operation, a rack and pinion mechanism for operating said printing roller, said mechanism being adapted to be moved in and out of engagement with said printing roller for varying its degree of rotation.

In testimony whereof I hereunto affix my signature.

ALBERT M. AYERS.
